WHEEL PUZZLE GAME BOARD

Joseph Raska, Berkley, Mich.

Application December 10, 1947, Serial No. 143,081

Term of patent 3½ years

(Cl. D34—5)

To all whom it may concern:

Be it known that I, Joseph Raska, a citizen of the United States and a resident of the village of Berkley, county of Oakland and State of Michigan, have invented a new, original, and ornamental Design for a Wheel Puzzle Game Board, of which the following is a specification, reference being had to the accompanying drawings forming a part hereof, in which:

The dominant features of my new design are shown in solid lines in the drawing.

I claim:

The ornamental design for a wheel puzzle game board, as shown and described.

JOSEPH RASKA.
